Attorneys.

UNITED STATES PATENT OFFICE.

GEORGE E. BROWN, OF LOS ANGELES, CALIFORNIA.

TABLE GOLF.

Application filed April 23, 1923. Serial No. 633,874.

To all whom it may concern:

Be it known that I, GEORGE E. BROWN, a citizen of the United States, residing at Los Angeles, in the county of Los Angeles and State of California, have invented new and useful Improvements in Table Golf, of which the following is a specification.

This invention relates to games, and has for its object to provide a miniature game

10 apparatus for playing the game of golf. Another object is to provide a golf game apparatus that may be conveniently played indoors and which apparatus is designed to be supported, for convenience, as upon a table or other elevated support so that the players may readily shift positions about the game apparatus to most effectively make the various strokes during play.

15 A further object is to provide a miniature golf game in which balls are propelled about the green through means of a golf club which is operative to impart a sharp blow or snap to the balls simulating the manner of driving and putting, it being against the 20 rules of the game to push the balls during play.

25 Another object is to provide a game apparatus having a field simulating a golf green and including the various well known and proper hazards such, for instance, as hills, ditches, mounds, depressions and water courses, which must be overcome in a manner similar to the playing of the standard game of golf.

30 A further object is to provide a game combining a playing field having a surface preferably of a somewhat yieldable character, and to provide a playing club having a resilient shank which is adapted to be bowed

35 or flexed under pressure when the head or striking end of the club is slightly pressed into the resilient or spongy surface of the field for the purpose of determining and controlling skillfully the blow imparted to the ball when the striking head is released from contact with the surface of the field.

40 An object is to provide a club which, during play, will produce what is known as a stroke, which consists of a movement of the ball by 45 a lofting action similar to the lofting strokes in the standard game.

45 A further object is to provide a ball which will practically be devoid of a rebounding tendency and which will, therefore, make it 50 practicable in playing the miniature game

by strokes imparting a lofting movement to the ball.

Other objects and advantages will be made manifest in the following specification of an embodiment of the invention illustrated in 60 the accompanying drawings, wherein—

Figure 1 is a perspective of the game field.

Fig. 2 is a sectional view of a portion of the field structure.

Fig. 3 is an elevation of one of the balls. 65

Fig. 4 is a diametrical section of a ball.

Fig. 5 is an elevation of the back of one of the clubs.

Fig. 6 is an elevation at right angles to the view of Figure 5, and looking toward the 70 striking end of the head of the club.

Fig. 7 is a perspective of a bag for receiving the clubs and balls of the game.

The game of the present invention consists of a topographic field 2 having an upper surface 3, which is given various contours and may be provided with a number of water courses 4, which may be formed with a polished metal surface or a mirror glass, various bunkers being shown at 5; the 75 surface irregularities and the water courses constituting the usual hazards in a field. At different positions in the top surface are provided the usual holes 6, into which the ball B is adapted to be played. 80

Obviously, any number of holes may be provided in the "green," and preferably the holes are numbered consecutively, and the game may be played either by playing 85 progressively from one hole to the other 90 according to number, or may be played by driving the ball by a stroke from the first, starting or permanent tee, designated 7 on the drawing.

When the game is played by strokes progressively from one hole to the next in order, the ball is played from a zone within a circle 8 surrounding each hole and which, therefore, constitutes the tee at the hole.

It is obviously an object of the game to 100 play all of the holes with the least number of strokes, and it is against the rules of the present game to deliberately bank the ball against a side fence 10, surrounding the field, with the object of having the ball 105 lodge in a favorable position for playing. In the event that the ball contacts with the fence in regular or proper play, no penalty is inflicted.

For playing, I provide a golf club, which 110

is shown substantially in full scale on the drawings and is about six inches in length. The club includes a handle portion 11, and at its lower end is provided with a shank 12 of 5 flexible, resilient material, shown here as of flat, spring steel. The lower end of the shank 12 is provided with a right angular striking head 13, and the effective face 14 thereof, Figure 6, is inclined upwardly and 10 rearwardly as to the direction of stroke so as to impart a desired lofting movement to the ball.

During play, the head of the golf club is pressed down firmly onto the surface 3 15 of the field or at the tees, and the shank is then bowed or flexed according to the assumed force required as determined by the length of the flight through which the ball is to be driven. The head of the club is de- 20 signed to be snapped against the ball and not placed in contact therewith in such manner as to result in a push.

Preferably, a ball B of a non-rebounding character is employed, and such a ball is 25 here shown as consisting of a solid, heavy core C with a composition covering or jacket j. Such a ball is designed to fall upon the surface without a material rebound and to roll along the surface after contact.

30 The rules of the game enable the same to be played by any number of persons.

If the ball is lifted, as out of a water hazard or an "impossible lie", one stroke should be counted for the lift. If the ball 35 is lifted from a water hazard it should be placed as nearly as may be possible in the same place from which the stroke was made. If the ball is lifted from an impossible lie, it should be moved only far enough to per- 40 mit the proper use of the club. Any motion imparted to the ball while in the act of addressing it that is more than the distance of its diameter shall be counted as a stroke. A ball striking a water hazard is considered 45 dead (even though it may roll out onto the green), and should be recovered and penalized by counting a stroke.

The fence 10 is shown as interiorly decorated to simulate the landscape around a 50 green, and for convenience one side of the fence may be provided with racks 16 to receive a golf club bag 17. The bag 17 is shown as provided with a side pocket 18 to receive the golf balls.

55 From this it will be seen that the game and the various parts and elements thereof may be kept in assembled and packed relation to prevent loss of parts when the game is not in use. Preferably, the apparatus is 60 provided with a cover which is not here shown.

The playing field may be built or may be of any suitable material possessing the desired degree of resiliency, and may be formed, for instance, of an asbestos composition or other porous, compressible material, to facilitate positioning of the clubs and the bowing of the same under pressure so as to obtain the "snap" action in making a stroke of the ball. 65 70

The covering or jacket added to the heavy central core is designed to build up the core to form a ball of the desired size. Also, the jacket provides means for obtaining the desired color and surface configurations or or- 75 namentations, if desired. The jacket may be of any suitable composition, for instance, plaster of Paris or other compounds.

Further embodiments, modifications and variations may be resorted to within the 80 principle of the invention.

What is claimed is:

1. A game apparatus consisting of a miniature topographic field having obstructions representing the usual hazards of the 85 game of golf, and holes at various portions of the surface of the field into which a played ball is to be driven, the field being formed of a material which will present a yieldable surface having a resilient base 90 into which a playing club can be slightly depressed in making a stroke.

2. In combination in a miniature golf game apparatus, a golf green having a field surface of slightly yieldable character and 95 a bendable golf club, the head of which is adapted to be slightly depressed into the surface of the green so as to have a snapping action in making a stroke of a ball.

3. In combination in a miniature golf game apparatus, a golf green having a field surface of slightly yieldable character, a bendable golf club, the head of which is adapted to be slightly depressed into the surface of the green so as to have a snapping action in making a stroke of a ball, and a ball of non-rebounding character. 100 105

4. A game apparatus consisting of a miniature topographic field having obstructions representing the usual hazards of the game of golf, holes at various portions of the surface of the field into which a played ball is to be driven, a teeing zone at each of the holes from which a ball is to be played, and a circular index formed of the surface material around each hole forming a tee from which a ball is to be played at the hole. 110 115

In testimony whereof I have signed my name to this specification.

GEORGE E. BROWN.
